UNITED STATES PATENT OFFICE.

PHILLIP SUSSELES, OF STATEN ISLAND, NEW YORK.

CAR-FENDER.

No. 923,213.

Specification of Letters Patent.

Patented June 1, 1909.

Application filed August 15, 1908. Serial No. 448,646.

To all whom it may concern:

Be it known that I, PHILLIP SUSSELES, a citizen of the United States, and residing at Staten Island, in the county of Richmond 5 and State of New York, have invented certain new and useful Improvements in Car-Fenders, of which the following is a specification, such as will enable those skilled in the art to which it appertains to make and use 10 the same.

This invention relates to tramway car fenders, and the object thereof is to provide an improved device of this class which will prevent the serious and sometimes fatal accidents which frequently result from a person being struck by a car while in motion; and with this and other objects in view the invention consists in a device of the class specified constructed as hereinafter described and 20 claimed.

The invention is fully disclosed in the following specification, of which the accompanying drawings form a part, in which the separate parts of my improvement are designated by suitable reference characters in each of the views, and in which:

Figure 1 is a side view of the end part of a platform of a tramway car and showing my improved fender connected therewith, part 30 of the construction being in section, Fig. 2 a section on the line 2—2 of Fig. 3, Fig. 3 a plan view of the device as shown in Figs. 1 and 2, Fig. 4 a partial section on the line 4—4 of Fig. 3 and Fig. 5 a side view of a 35 tail of the construction which I employ.

In the drawings forming part of this specification, I have shown at *a* one end platform of a tramway car provided with the usual dash-board *a*², and beneath the platform *a* is placed a transverse keeper *a*³ having an outwardly directed segmental extension *a*⁴, and in the practice of my invention I provide a main yoke-shaped cross head *b* having forwardly directed side arms *b*² and a central 45 backwardly directed shank *b*³ which is pivoted at *b*⁴ in the keeper *a*³ centrally thereof, and said cross head *b* is free to swing in a horizontal plane through an arc of approximately ninety degrees.

50 A shaft *c* is mounted in and passes through the ends of the side arms *b*² of the cross head *b*, and mounted thereon is a main frame *d*

composed, in the form of construction shown, of side members *d*², a front transverse rod *d*³, a bottom transverse bar *d*⁴ and rear transverse rods *d*⁵ and *d*⁶.

Mounted forwardly of the transverse bar *d*⁴ and between the same and the rod *d*³ is a shaft *e* on which are mounted flanged wheels *e*² adapted to travel on the rails of a track indicated at *x* in Fig. 3, and on the rails of a switch indicated at *x*².

Pivoted forwardly of the transverse front rod *d*³ is a supplemental frame *f* composed, in the form of construction shown, of side members *f*² connected by a transverse bar *f*³, and the supplemental frame *f* is adapted to swing in a vertical plane as shown in dotted lines in Fig. 1. Loosely mounted on the rod *d*³ on which the front supplemental frame *f* is pivoted and centrally thereof, is a backwardly directed arm *f*⁴, and pivoted rearwardly of the rod *d*³ and to the inner sides of the side members *d*² of the main frame *d* as shown at *f*⁵ is a rearwardly directed yoke-shaped frame *g* composed of backwardly directed side arms, the rear ends of which are connected by a cross rod *g*², and the rear end of the arm *f*⁴ bears on the cross rod *g*² of the yoke-shaped frame *g* as shown in Figs. 2 80 and 3.

Stop plates *g*³ are secured to the inner sides of the side members *f*² of the supplemental frame *f*, and are provided with shoulders *g*⁴ and *g*⁵, and the ends of the side members of the yoke-shaped frame *g* are provided with forwardly directed dogs *g*⁶ which are adapted to operate in connection with the shoulders *g*⁴ and *g*⁵ of the stop plates *g*³, and when these parts are in the position shown in Fig. 4, the front supplemental frame *f* is held in its normal position, and when the dogs *g*⁶ operate in connection with the shoulders *g*⁵ the supplemental frame *f* is held in the position shown in dotted lines in Fig. 1 as hereinafter 95 described.

A spiral spring *g*⁷ is wound on the transverse rod *d*⁵, and the end portions thereof are oppositely wound on the end portions of said rod as clearly shown in Fig. 3, and the end portions of said spring are formed into forwardly directed fingers *g*⁸ which pass beneath the transverse cross rod *g*² of the yoke-shaped frame *g* and serve to normally hold said

frame in the position shown in Figs. 2 and 4 so as to hold the supplemental frame *f* in its normal or operative position. The shaft *c* is also provided with a spring *h* which is secured thereto and wound thereon in opposite directions and the end portions of which are provided with forwardly directed spring fingers *h*² which are connected with the rear transverse rod *d*⁶ of the main frame, and the object of which is to depress the main frame and hold it in proper operative position with the wheels *e*² on the rails of the track, and the shaft *c* is provided at one end with a ratchet *h*³ and the end *h*⁴ of said shaft is formed so that a crank can be applied thereto and the spring *h* on said shaft may be wound up by turning said shaft in the forward direction, and the backward movement of said shaft is prevented by a pawl *h*⁵ pivoted to the cross head *b* rearwardly of said shaft and operating in connection with the ratchet *h*³.

The front end portion of the front supplemental frame *f* is connected with the rear end portion of the main frame *d* by spiral side springs *h*⁶ which normally serve to pull the supplemental frame into the position shown in dotted lines in Fig. 1 when the dogs *g*⁶ of the yoke-shaped frame *g* are thrown out of engagement with the shoulders *g*⁴ of the stop plates *g*³, at which time the supplemental frame *f* is thrown upwardly and the dogs *g*⁶ operate on the shoulders *g*⁵ and stop the backward movement of the supplemental frame *f*.

The side portions of the front supplemental frame *f* are connected by transversely arranged spirally wound elastic guards *i*, and the side portions of the main frame are connected by transversely arranged spirally wound elastic guards *i*² which extend the full length of the main frame *d* and the front supplemental frame *f*. I also employ a rear supplemental frame *j* composed, in the form of construction shown, of side members *j*³, a transverse bar *j*³ and transversely arranged spirally wound elastic guard members *j*⁴, and the side members *j*³ of which are provided at their lower ends with forwardly directed ears *j*⁵ as shown in Fig. 5, and said ears are mounted on the shaft *c* at the sides of the rear end portions of the side members *d*² of the main frame and form in connection therewith a hinge as shown at *g*⁹ in Fig. 3, and the rear supplemental frame is stationary and is normally held in the position shown in Figs. 1 and 2, the forward movement thereof being prevented by the lower ends of the side members *j*³ thereof, which press against the cross head *b*, while the main frame *d* is free to swing vertically as indicated in dotted lines in Fig. 1 on the hinges at *g*⁹, and in practice I connect with the dash-board *a*² hooks *k* which are adapted to be engaged with the

supplemental frame *f* as shown in Fig. 1 and hold the main and supplemental frames in the position shown in dotted lines in Fig. 1 whenever necessary or desirable.

The operation will be readily understood from the foregoing description when taken in connection with the accompanying drawings and the following statement thereof. Suppose the parts to be in the position shown in Fig. 2 and the car is in motion. If now a person be struck by the supplemental frame *f* of the fender, such person will be thrown back onto the main frame and onto the transverse elastic guards *i*² and the front transversely arranged elastic guards *i*² will be depressed onto the arm *f*⁴ and the rear end portion of the yoke-shaped frame *g* will be depressed against the operation of the spring fingers *g*⁸ and the dogs *g*⁶ will be raised out of engagement with the shoulders *g*⁴, on the stop plate *g*³ and the supplemental frame *f* will be thrown into the position shown in dotted lines in Fig. 1, and such person will be held on the main frame of the fender, or will not be allowed to slide forwardly therefrom onto the track, and in this operation the side springs *h*⁶ also serve as guards to hold such person on the main frame of the fender or guard, while the rear supplemental frame *g* prevents such person from being thrown backwardly against the end of the platform or the dash-board, and in this operation the transverse elastic guards *i*, *i*² and *j*⁴ prevent the person from being injured. The front transverse elastic guard *i* of the supplemental frame *f* also prevents a person from being injured when first struck by the car, or the fender or guard when the car is in motion, and it will be understood that the supplemental frame *f* may be again pulled down into its operative position as shown in full lines in Figs. 1, 2 and 4, in which operation the dogs *g*⁶ of the frame *g* engage the shoulders *g*⁴ of the stop plates *g*³ and hold said supplemental frame in said position against the tension of the side springs *h*⁶.

It will also be understood that my improved fender or guard is adapted to swing in a horizontal plane as indicated in dotted lines in Fig. 3 whenever the car is making a turn or taking a switch, this result being accomplished by reason of the pivotal support at *b*⁴, and the fact that the wheels *e*² always travel on the rails of the track. This is one of the main features of my invention, and by reason thereof the fender or guard will take the curve or the switch before the car and will occupy much less space in turning and will not interfere with another car or the fender or guard thereof when coming in an opposite direction on a corresponding track, and the fender or guard will also not be so

apt to strike a person or object at one side of the switch or one side of the turn or curve in the track.

It will be understood that the front end of the platform is curved or rounded as indicated at m in Fig. 3 so as to permit of the fender or guard being held closely to the car and to turn around the end thereof or around the end of the platform as herein described 10 and as shown in Fig. 3.

I also secure to the bottom of the cross head b a suitable keeper n in which is mounted a horizontal and forwardly and backwardly movable coupler bar n^2 , the front end 15 of which is provided with a head n^3 having an aperture n^4 , the object of this construction being to provide means whereby one car may be hitched onto another so as to pull the latter, when the fender or guard is raised into 20 the position shown in dotted lines in Fig. 1, and the coupler bar n^2 is provided with a spring n^5 which normally holds it in a retracted position and out of the way of the main frame of the fender or guard when the 25 latter is in operative position as shown in Fig. 1.

The rear supplemental frame j is not an absolutely essential feature of my improved fender or guard, but I prefer to employ the 30 same for the purpose herein set out.

Having fully described my invention, what I claim as new and desire to secure by Letters Patent, is;

1. In a fender or guard for tramway cars, 35 a cross head member mounted beneath and pivoted beneath the platform and extending forwardly thereof and adapted to automatically swing in a horizontal plane, and a fender frame pivoted to said cross head 40 member and adapted to swing in a vertical plane and normally extending downwardly and forwardly and provided at its front end with wheels adapted to travel on the rails of the track, and to swing the fender frame and 45 cross head laterally in turning curves.

2. In a fender or guard for tramway cars, 50 a cross head member mounted beneath and pivoted beneath the platform and extending forwardly thereof and adapted to swing in a horizontal plane, and a main frame pivoted to said cross head member and normally extending downwardly and forwardly and provided at its front end with wheels adapted to travel on the rails of the track, said main 55 frame being provided at its front end with a supplemental frame normally held in a depressed position and adapted to be thrown upwardly and held in a raised position when a person or object is struck thereby.

60 3. In a fender or guard for tramway cars, a cross head member mounted beneath and pivoted beneath the platform and extending

forwardly thereof and adapted to swing in a horizontal plane, and a main frame pivoted to said cross head member and normally extending downwardly and forwardly and provided at its front end with wheels adapted to travel on the rails of the track, said main frame being provided at its front end with a supplemental frame normally held in a depressed position and adapted to be thrown upwardly and held in a raised position when a person or object is struck thereby, both of said parts being provided with transverse elastic guards. 75

4. In a fender or guard for tramway cars, a cross head member mounted beneath and pivoted beneath the platform and extending forwardly thereof and adapted to swing in a horizontal plane, and a main frame pivoted to said cross head member and normally extending downwardly and forwardly and provided at its front end with wheels adapted to travel on the rails of the track, said main frame being provided at its front end with a supplemental frame normally held in a depressed position and adapted to be thrown upwardly and held in a raised position when a person or object is struck thereby, both of said parts being provided with transverse elastic guards, and the front end of the front supplemental frame being connected with the rear end of the main frame by elastic side guards. 90

5. In a fender or guard for tramway cars, 95 a cross head member mounted beneath and pivoted beneath the platform and extending forwardly thereof and adapted to swing in a horizontal plane, and a main frame pivoted to said cross head member and normally extending downwardly and forwardly and provided at its front end with wheels adapted to travel on the rails of the track, said main frame being provided at its front end with a supplemental frame normally held in a depressed position and adapted to be thrown upwardly and held in a raised position when a person or object is struck thereby, and a rear supplemental frame connected with the rear end portion of the main frame and normally supported in front of the dash-board of the car. 105

6. A fender or guard for tramway cars, comprising a cross head member pivotally supported beneath the platform of a car and 110 extending forwardly thereof and adapted to swing in a horizontal plane, and a fender or guard frame hinged to said cross head member and normally extending forwardly and downwardly and provided at its front end with wheels adapted to travel on the rails of the track, and to automatically swing the fender or guard frame and the cross head laterally in turning curves. 120

7. A fender or guard for tramway cars supported in front of a platform thereof and adapted to fold vertically and to be held in an upright position and normally extending 5 downwardly and forwardly, said fender or guard being provided at its front end with a supplemental member adapted to be folded upwardly, means for holding said supplemental member normally in a depressed position, and means for raising said supplemental member when a person is struck

thereby and thrown backwardly onto the fender or guard.

In testimony that I claim the foregoing as my invention I have signed my name in 15 presence of the subscribing witnesses this 13th day of August, 1908.

PHILLIP SUSSELES.
